UNITED STATES PATENT OFFICE.

HENRY L. DEMMLER, OF KEWANEE, ILLINOIS.

MOLD-MAKING MACHINE.

Application filed September 14, 1923. Serial No. 662,602.

The present invention relates to machines for making molds or cores by forcing sand into a flask or core box by compressed air or other pressure fluid. The principal object of the invention is the provision of means for pneumatically operating the various parts of the machine and for controlling the operations by conveniently accessible valves. In machines in which sand is forced into the flask or core box by compressed air it is necessary to provide for a comparatively heavy blast of air for this purpose. It is an important object of the present invention to operate the valve which controls the main air blast pneumatically by means of a valve conveniently operable at the will of the operator. Other objects of the invention will appear in the following description.

In the drawings, which illustrate a preferred embodiment of the invention:

Figure 1 is an end elevation of a machine embodying the invention.

Figure 2 is a vertical section on the line 2—2 in Figure 1.

Figure 3 is an enlarged sectional view of the main blast valve on the line 3—3 in Figure 2.

Figure 4 is an enlarged sectional view of a control valve on the line 4—4 in Figure 2.

Figure 5 is a front elevation of the control valve.

Figure 6 is an enlarged top plan of another control valve.

Figure 7 is a section on the line 7—7 in Figure 6.

Figure 8 is a section on the line 8—8 in Figure 2.

Figure 9 is a broken sectional view of a modified form of the main blast valve.

In the machine illustrated in the drawings the mold or core is to be formed in the flask or core box 1 and hereafter the word flask will be used to comprehend all mold forms. The flask 1 is removably supported on a table 2 and during formation of the mold the flask is to be clamped against the sand container 9. The table 2 is formed as a cylinder slideable on a piston 3 which is supported in the frame by a screw 4 so that the piston and table may be vertically adjusted to accommodate different flasks. The table 2 is provided with pins 5 extending slidably through the piston 3 and formed with heads to limit upward movement of

the table. The table is normally held in lower position by gravity and is movable upwardly to clamp a flask against the sand container by compressed air supplied to the space between the under side of the table 60 and the piston head through a flexible pipe 6 connected with a port 7 of valve casing 8.

The flask 1, in addition to being clamped against the sand container 9 by the table 2, may be laterally secured between the 65 clamps 10. Each of the opposing clamps 10 is carried by a piston 11 reciprocable in a cylinder 12 secured to the table 2. The piston 11 with its clamp 10 is normally held in retracted position by a spring 13 and 70 may be moved forwardly to clamping position by compressed air supplied against the outer face of the piston. Compressed air is supplied to one of the pistons (the one to the left in Figure 2) by a flexible pipe 14 75 connected with the same port 7 of valve casing 8 with which is connected the pipe 6 supplying compressed air to raise the table 2. The other piston 11 is supplied with compressed air through the flexible pipe 15 80 connected with a valve casing 16.

When the flask is clamped in position in registration with the sand container 9 it is adapted to be filled with sand forced from the container into the flask by a blast of 85 compressed air admitted through the valve casing 17. Referring especially to Figure 3, the valve casing 17 is formed with an inlet port 18 to be connected with a source of compressed air and with an outlet port 90 or passage 19 directed into the sand container. The ports 18 and 19 are of relatively large area so that a heavy blast of air may be directed into the sand container. Preferably the port 19 is formed with baffles 95 20 and 21. Air is constantly admitted to the valve casing through the inlet port 18 but the outlet port is alternatively opened or closed by a slide valve 22. The valve 22 is provided with a valve rod 23 carrying a cup leather piston 24 slidably fitted in a cylindrical portion 25 of the valve casing. The valve is normally held in the open position shown in Figure 3 by pressure of the air in the casing against the inner face of the piston 24. The valve may be moved to closing position by compressed air supplied to the outer face of the piston 24 through a flexible pipe 26, aided by a compression spring 28. The pipe 26 is connected with 110

a port 27 of valve casing 8. The valve rod may be provided with a cushion 29 for the purpose of cushioning the return of the valve to normal position when air is exhausted from the pipe 26. The valve casing 17 is provided with a relief port 30 opening to atmosphere from the port 19 between the valve 22 and the outer end of the port. The relief port 30 is controlled by a valve 31 hinged on a shaft 32, the valve 31 being provided with a screw-adjustable flexible block 33 adapted to close the outer end of the relief port 30 when the valve 31 is swung on the shaft 32. The valve casing 8 through which the table 2, one of the clamps 10, and the valve 22 are controlled is illustrated in detail in Figures 4 and 5. The casing is provided with a pipe 34 for the constant supply of compressed air to the casing. The casing, in addition to the port 7 through which compressed air is supplied to the table 2 and the clamp 10, and the port 27 through which air is supplied to control the main valve 22, is provided with an exhaust port 35. The ports are controlled by a slide valve 36, the valve rod 37 being flexibly connected with a treadle 38 and normally held in raised position, as illustrated in Figure 4, by a spring 39. (In the claims 30 the valve 36 is referred to as manually operable, this phrase being intended to include hand and foot operation in distinction to automatic or mechanical operation.) In this position the pipe 6 opening below the table 2 and the pipe 14 opening behind the clamp piston 11 are connected with the exhaust port 35 so that the table and clamp are retracted; the pipe 26 is open to the passage of air from the supply pipe 34 so that 40 pressure is supplied against the outer face of the piston 24 to hold the main valve 22 in closed position, in alternation to the open position in which it is illustrated in Figure 3.

45 The valve 31 controlling the relief port 30 is provided with a rod 40 normally held in raised position to open the relief port by a spring 41 but compressible by a link 42 connected with the treadle 38. When the 50 treadle is depressed to connect the pipe 26 with the exhaust port 35 in valve casing 8 and thus permit the main valve 22 to open, the valve 31 is depressed to close the relief port 30.

55 The sand container 9 is carried by a support 43 which is horizontally movable on rollers 44 secured to the frame of the machine. The sand container is preferably open at its top for the admission of sand 60 and the air blast through the main valve casing 17 and is provided with a bottom plate perforated for the discharge of sand and air into the flask. The support 43 is normally held so that the sand container is not positioned over the table 2 (to the right of the

position shown in Figure 2) by a cable connected with a spring 45. The support 43 carrying the sand container 9 may be moved to position the sand container over the table 2 by supplying compressed air against a piston 46 connected with the sand container by a rod 47, the piston being slidably in a cylinder 48 connected by a pipe 49 with a valve casing 50.

When the support 43 is in normal position, to the right of the position shown in Figure 2, the sand container 9 is positioned below a sand supply hopper 51. The support 43 is in form a plate so that when it is moved to position the container over the table 2, the support or plate 43 closes the outlet from the hopper 51. It is important that sand supplied from the hopper 51 to the sand container 9 be firmly compacted in the container before it is subjected to the blast by which it is forced into the flask. This mode of operation provides for the formation of a much more accurate and solid mold in the flask. For this purpose a cylinder 52 is supported above the hopper 51 and slidably therein is a piston 53 carrying a plunger 54. The piston and plunger are normally held in raised position by a weight 55 supported by a cable 56 extending through a groove 57 in the rod connecting the piston 53 and plunger 54 and secured to the lower end of the rod. The piston and plunger are compressible by compressed air admitted against the upper face of the piston 53 through a pipe 58 connected with a valve casing 59.

It is often desirable to stir the sand in the hopper 51 so that it will flow freely into the sand container. For this purpose the sleeve in which the rod of plunger 54 slides supports a rotatable sleeve 60 carrying stirring blades 61 and a gear 62. The latter meshes with a pinion 63 fixed on a shaft 64 rotatable by any desired means such as the application of power to a pulley 65.

After the sand has been blown into the flask 1 to form a mold it is often desirable to ram the mold still further to compact the sand forming it. The support 43 carries a cylinder 66 in which is fitted a piston 67 carrying a ram 68 normally held in raised position by a spring 69. The ram is compressible by the supply of compressed air against the upper face of the piston 67 through a flexible pipe 70 connected with the same port of valve casing 59 with which is connected the pipe 58 supplying compressed air to depress the plunger 54. The sand container 9 and the ram 68 are supported from the movable support 43 in such relative positions that when the sand container is positioned below the hopper to receive a new supply of sand the ram 68 will be positioned over the flask in which a mold has just been formed.

The valve casing 16 controlling one of the clamps 10, the valve casing 50 controlling movement of the support 43 carrying the sand container and ram 68, and the 5 valve casing 59 controlling depression of the rams 54 and 68, are of the same construction. One of these, the valve casing 59, is illustrated in detail in Figures 6 and 7. The casing is provided with a pipe 71 for the constant admission of compressed air, the pipe 71 supplying the valve casings 59, 16 and 50 in common. The casing is provided with an outlet port 72 with which the pipes 58 and 70 are connected. The corresponding port of valve casing 16 is connected with pipe 15 and the corresponding port of valve casing 50 is connected with pipe 49. The valve casing 59 encloses a disk valve 73 formed with a port 74 through which compressed air from pipe 71 is supplied through port 72 when port 74 is brought into register with the latter. The casing is also provided with an exhaust port 75 with which the port 72 may be connected 25 by a passage 76 formed in the valve 73 when the latter is rotated to proper position.

The machine is operated in the following manner. Looking at Figure 2, assume that air is exhausted from below the table 2 so that the flask 1 is lowered from contact with the sand container 9; and that air is exhausted from behind both pistons 11 so that the clamps 10 are in retracted position. The operator then rotates the valve in valve 33 casing 50 to exhaust air from the cylinder 48, whereupon the spring 45 moves the support 43 to the right to position the sand container 9 under the hopper 51 and the ram 68 over the flask 1. The operator next rotates the 40 valve in valve casing 16 to supply air behind the piston of the right hand clamp 10, thus clamping the flask against the other clamp 10. Sand now flows from the hopper into the sand container and the operator rotates the valve in valve casing 59 to supply air against the pistons 53 and 67, thus depressing the ram 54 to compact sand in the container 9 and depressing ram 68 to solidify the mold in the flask 1. The valve in casing 45 50 is then rotated to exhaust air from the cylinders 52 and 66 permitting the rams to rise. The operator then rotates the valve in casing 16 to exhaust air from behind the piston 11, thus releasing the flask which is 55 removed from the machine. The valve in casing 50 is then rotated to admit air to the cylinder 48 to move the support 43 to position the sand container under the valve casing 17, as illustrated in Figure 2. A new flask is placed on the table 2 below the sand container. The operator then depresses the treadle 38 to move the valve 36 downwardly from the position in which it is shown in Figure 4. As the valve moves downwardly 60 65 it permits the supply of compressed air from pipe 34 through pipes 6 and 14, thus raising the table 2 to clamp the flask against the sand container and advancing the left clamp 10 to clamp the flask against the other clamp 10. Almost simultaneously the valve also opens the pipe 26 to the exhaust port 35 permitting the escape of air from behind the piston 24 so that the compressed air in the casing 17 opens the main valve 22, so that a heavy blast of air is directed into the sand 70 75 container to force sand therefrom into the flask. Depression of the treadle 38 at the same time swings the valve 31 downwardly to close the relief port 30 in the main valve casing. The mold is formed almost instant- 80 85 ly, whereupon the operator releases the treadle 38 so that the spring 39 reverses the valve 36 into the position in which it is shown in Figure 4. In this position air is supplied against the outer face of the piston 24, thus closing the main valve and almost instantaneously the pipes 6 and 14 are connected with the exhaust port 35 to retract the table 2 and clamp 10 and free the flask. When the treadle is released the spring 41 raises the valve 31 to open the relief port 30 through which any excess pressure in the sand container is dissipated. The sequence of operations is then repeated.

The main blast valve may, if desired, be 90 95 constructed as shown in Figure 9 instead of as shown in Figure 3. In Figure 9 the valve casing 80 is substantially similar to the casing 17 and has an inlet port connected with the outlet port or passage 19. The valve 81 controlling the outlet port is secured to a stem 82 on which is mounted a differential piston. The differential piston comprises a smaller face or piston 83 slidable in a cylinder 84 and a larger face or piston 85 slidable in a cylinder 86. The opposite end of the stem 82 extends through suitable packing 88 and is provided with a head 89 to limit movement of the valve mechanism. In this form of valve pressure of fluid admitted to the casing through the inlet port 100 normally holds the valve in one position, preferably open position, by pressure against the smaller piston 83. The valve may be moved to closed position by admission of 105 pressure fluid against the outer face of the larger piston 85 through a pipe 87 controlled as is the pipe 26 in Figure 3. When pressure is exhausted from the face of the piston 85 the valve automatically returns to normal 110 115 position.

Having thus described my invention, what I claim is:

1. In a molding machine, a sand container, a valve casing having a passage for supplying fluid under pressure to the container to force sand into a flask, a valve in said casing for controlling said passage, a piston connected to said valve and exposed at one 120 125 face to the fluid in said casing, a second con-

- duit for the supply of fluid to and from the opposite face of the said piston and a valve controlling the two said conduits alternately.
2. A valve mechanism comprising, a casing having a conduit therethrough, a valve for closing said conduit, a piston connected to said valve and exposed at one face to the fluid in said casing for moving said valve in one direction under the influence of the fluid in the casing, and means for supplying fluid to the other face of said piston to move the valve in the opposite direction.
3. A valve mechanism comprising, a casing having a tortuous conduit therethrough, a valve for closing said conduit, a piston connected to said valve and exposed at one face to the fluid in said casing for moving said valve in one direction under the influence of the fluid in the casing, and means for supplying fluid to the other face of said piston to move the valve in the opposite direction.
4. A valve mechanism for the purpose described comprising, a casing having a primary conduit therethrough and a pressure relief conduit from said primary conduit, a valve for closing said conduit, fluid pressure actuated means connected to said valve and exposed to the fluid entering said casing for moving said valve in one direction, means for supplying fluid to said fluid pressure actuated means for moving said valve in the other direction, and means for opening and closing said relief conduit.
5. A valve mechanism for the purpose described comprising, a casing having a conduit therethrough, a valve for closing said conduit, fluid pressure actuated means connected to said valve and exposed to the fluid entering said casing for moving said valve in one direction, means for supplying fluid to said fluid pressure actuated means and casing for moving said valve in opposite directions, and means for controlling said supply means.
6. In a molding machine, the combination of a sand container, a valve casing having a passage for supplying fluid under pressure to the container to force sand into a flask, a valve in the casing controlling the passage and operable under pressure of fluid supplied thereto to open said passage, said casing having a relief port between the valve and the container, a valve controlling said relief port, and means for controlling said relief port valve whereby it will be closed simultaneously with the opening movement of the valve controlling the passage in the casing, and vice versa.
7. In a molding machine, the combination of a sand container, a valve casing having a passage for supplying pressure fluid to the container to force sand into a flask, a valve in the casing controlling the passage, the passage having a relief port between the valve and container, a conduit for the passage of pressure fluid to control the valve, a valve controlling the conduit, a valve controlling the relief port, and means for simultaneously operating the two last-named valves to open the passage and close the relief port and vice versa.
8. In a molding machine, the combination of a sand container, a valve casing having a passage for supplying pressure fluid to the container to force sand into a flask, a valve in the casing controlling the passage, the passage having a relief port between the valve and container, a conduit for the passage of pressure to control the slide valve, a valve controlling the conduit, a hinged valve controlling the relief port, and means for moving the conduit-controlled-valve to open the passage and for simultaneously swinging the hinged valve to close the relief port and vice versa.
9. In a molding machine, the combination of a sand container, a clamp reciprocable toward and from the container, a first conduit for the passage of pressure fluid to control the clamp, a valve casing having a passage for supplying pressure fluid to the container to force sand into a flask, a valve in the casing controlling the passage, the valve having a piston having one face exposed to pressure fluid in the casing, a second conduit for the passage of pressure fluid to and from the opposite face of the piston, a valve casing having ports respectively connected with the two conduits and having an exhaust port, and a valve in the last named casing adapted to connect the respective ports alternatively with a supply of fluid pressure and the exhaust port.
10. In a molding machine, the combination of a sand container, a vertically reciprocable clamp below the container, a horizontally reciprocable clamp between the container and first clamp, a first conduit for the supply of pressure fluid to move the clamps to clamping position, a valve casing having a passage for supplying pressure fluid to the container to force sand into a flask, a valve in the casing controlling the passage, the valve having a piston having one face exposed to pressure fluid in the casing and movable thereby to open the valve, a second conduit for the supply of pressure fluid to the opposite face of the piston, a valve casing having ports respectively connected with the two conduits and having an exhaust port, and a valve in the last named casing adapted in alternative positions to open one of the conduits to a supply of pressure fluid and the other to the exhaust port.
11. In a molding machine, the combination of a vertically reciprocable plunger, a second vertically reciprocable plunger hori-

zontally movable relatively to the first plunger, and means for simultaneously reciprocating the plungers.

12. In a molding machine, the combination of a vertically reciprocable plunger, a support movable relative to said plunger in a direction transverse to its direction of reciprocation, a sand container carried by the support and adapted to be positioned in register with the plunger, a second vertically reciprocable plunger carried by the support, and means for simultaneously reciprocating the plungers.

13. In a molding machine, the combination of a table, a fluid pressure supply device above the table, a hopper, a horizontally movable support, a sand container carried by the support and adapted to be positioned alternatively in register with the device or the hopper, a vertically reciprocable plunger carried by the support and adapted to be positioned above the table, a plunger vertically reciprocable in the hopper, and means for simultaneously reciprocating the plungers.

14. In a molding machine, the combination of a table, a fluid pressure supply device above the table, a hopper, a horizontally movable support, a sand container carried by the support and adapted to be positioned alternatively in register with the device or the hopper, a vertically reciprocable plunger carried by the support and adapted to be positioned above the table, a plunger vertically reciprocable in the hopper, the plungers being provided with pressure depressible pistons, means tending to hold the plungers in raised position, a conduit for the supply of pressure fluid to the pistons, and a manually operable valve controlling the conduit.

15. In a molding machine, the combination of a reciprocable plunger, a second reciprocable plunger movable relatively to the first plunger transversely of the direction of reciprocation, and means for simultaneously reciprocating the plungers.

16. In a molding machine, the combination of a sand container, a reciprocable plunger for compacting sand in the con-

tainer, means for securing a mold form to the container, and means for forcing sand from the container into the form by gaseous fluid pressure.

17. In a molding machine, the combination of a sand container, means for securing a mold form to the container, means for forcing sand from the container into the form by gaseous fluid pressure, and a reciprocable plunger for ramming the sand in the form.

18. In a molding machine, the combination of a sand container, a sand supply device, means for agitating the sand in the device to feed the sand into the container and pneumatically operable means for operating within said device for compacting sand into the container.

19. In a molding machine, the combination of a hopper, a sand container, a member revoluble in the hopper to feed sand into the container, and a reciprocable plunger operating within the hopper for compacting sand in the container.

20. In a molding machine, the combination with a hopper having discharge opening at its lower end, of a sand container adapted to be disposed below said discharge opening, a vertically reciprocal plunger operating within the hopper for compacting sand in the container, and an agitating means for the sand located within the hopper and rotatably mounted about the plunger.

21. In a molding machine, the combination with a hopper having discharge opening at its lower end, of a sand container adapted to be disposed below said discharge opening, a vertically reciprocal plunger operating within the hopper for compacting sand in the container, and an agitating means for the sand located within the hopper and rotatably mounted about the plunger, said agitating means comprising a sleeve surrounding said plunger, agitating blades fixed to said sleeve, and means for rotating said sleeve.

In witness whereof, I hereunto subscribe my name this 10th day of September, 1923.

HENRY L. DEMMLER.
